Primary Examiner—Ian Simmons*Assistant Examiner*—Wan Laymon(74) *Attorney, Agent, or Firm*—Townsend and Townsend and Crew LLP(57) **CLAIM**

The ornamental design for a camera with scroll wheel, as shown and described.

DESCRIPTION

FIG. 1 is a perspective view of a camera with scroll wheel showing our new design;

FIG. 2 is a front elevational view thereof;

FIG. 3 is a right elevational view thereof;

FIG. 4 is a rear elevational view thereof;

FIG. 5 is a left elevational view thereof;

FIG. 6 is a top plan view thereof; and,

FIG. 7 is a bottom plan view thereof.

The broken lines in the Figures are for illustrative purposes only and form no part of the claimed design.
